CLAIM

The ornamental design for a racing simulator cockpit, as shown and described.

DESCRIPTION

FIG. 1 is a front perspective view of a racing simulator cockpit embodying the new design;

FIG. 2 is a back perspective view thereof;

FIG. 3 is a left side view thereof;

FIG. 4 is a right side view thereof;

FIG. 5 is a back view thereof;

FIG. 6 is a front view thereof;

FIG. 7 is a top view thereof; and

FIG. 8 is a bottom thereof.

FIG. 9 is a front perspective view of the racing simulator cockpit with a chair portion removed for clarity;

FIG. 10 is a back perspective view thereof;

FIG. 11 is a left side view thereof;

FIG. 12 is a right side view thereof;

FIG. 13 is a back view thereof;

FIG. 14 is a front view thereof;

FIG. 15 is a top view thereof; and,

FIG. 16 is a bottom thereof.

Broken lines are used to illustrate features of the racing simulator cockpit that form no part of the claimed design. In embodiments other than those illustrated, lines that are currently illustrated as solid lines may be redrawn as broken lines, and/or lines that are currently illustrated with broken lines can be redrawn with solid lines. The scope of the present disclosure encompasses all lines illustrated, whether broken or solid. FIGS. 9-16 illustrate the racing simulator cockpit of FIGS. 1-8 with an unclaimed chair portion removed for clarity.
